ATTORNEYS

UNITED STATES PATENT OFFICE.

BENONI COLVIN, OF FREEPORT, ILLINOIS.

HAND-TRUCK.

SPECIFICATION forming part of Letters Patent No. 227,489, dated May 11, 1880.

Application filed March 13, 1880. (No model.)

To all whom it may concern:

Be it known that I, BENONI COLVIN, of Freeport, in the county of Stephenson and State of Illinois, have invented certain new and useful 5 Improvements in Hand-Trucks; and I do hereby declare that the following is a full, clear, and exact description of the construction and operation of the same, reference being had to the annexed drawing, making a part of 10 this specification, and to the letters and figures of reference marked thereon.

The figure of the drawing is a perspective view of my hand-truck.

My invention relates to hand-trucks; and it 15 consists in the construction of parts, as hereinafter described and claimed.

The truck consists of three bars arranged and braced as follows: The side bars, A, have the straight portions *a*, which curve upwardly 20 to form handles *a'*. The central bar, B, has the straight part *b*, which curves up and then round to form the overhanging straight part *b'*.

C C' C² are three cross brace-bars, and D is a brace-rod passing through the curved parts 25 of all three bars. This frame is supported on rollers E, the axles of which are journaled in the bearings *e*.

F F' are brace-rod extending from the bars A to the overhanging portion of bar B. The 30 overhanging portion of bar B is slotted, as at G, to receive a lever, H, which is pivoted in the forward end of the slot.

The lever has grappling-hooks I, so that a box or bale may be grappled, and by operating the lever the article can be swung on the 35 truck, the lower horizontal portions of the three bars constituting a base for the same to rest on. The slot is of considerable length, so as to allow free play of the lever.

This arrangement forms a cheap, simple, 40 strong, and desirable truck.

What I claim is—

1. In a truck, the side bars, A, and the central bar, B, said side bars having the straight portions *a*, and the central bar having a straight 45 part, *b*, which curves upwardly and extends forward to form the straight overhanging and slotted part *b'*, said overhanging part being provided with a pivoted lever having grappling-hooks, substantially as set forth. 50

2. A truck composed of the three bars A, A, and B, having the straight and curved parts, as set forth, said bars being braced and supported upon rollers, as specified.

In testimony that I claim the above I have 55 hereunto subscribed my name in the presence of two witnesses.

BENONI COLVIN.
